UNITED STATES PATENT OFFICE.

ABRAHAM HARTMAN, OF NEW YORK, N. Y.

MATTRESS.

1,175,260.

Specification of Letters Patent. Patented Mar. 14, 1916.

Application filed May 29, 1915. Serial No. 31,132.

To all whom it may concern:

Be it known that I, ABRAHAM HARTMAN, a citizen of the United States, and a resident of New York city, borough of Manhattan, 5 in the county of New York and State of New York, have invented certain new and useful Improvements in Mattresses, of which the following is a specification.

This invention relates to new and useful 10 improvements in mattresses.

The object of my invention is to provide a new and improved mattress of simple construction, strong and durable, which can be used like any ordinary mattress, can be reversed so that either surface can be used as the top and which has an adjustable head rest, which can be adjusted at various degrees of inclination to extend upward from the top surface of the mattress and when the 20 mattress is reversed can also be adjusted to project upward.

In the accompanying drawings in which like letters of reference indicate like parts in all the figures: Figure 1 is a perspective 25 view of one end of my new and improved mattress, showing one flap adjusted at an inclination to the body of the mattress. Fig. 2 is a side view of the mattress, adjusted in the same manner. Fig. 3 is a similar view 30 showing the mattress reversed.

The mattress 1 has its body constructed in any well known manner and can be stuffed with horse hair, moss, cotton or any well known stuffing material, for mattresses. At 35 one end the mattress is split horizontally, that is, from one side edge to the other to form two flaps or bolsters 2, 2, which are integral with the body of the mattress. The upper and lower outer covering layers 3 and 40 4 of the mattress, preferably consisting of ticking, such as is usually used for making mattresses, extend in one piece each, over the body of the mattress and the corresponding bolster. Likewise the sides 5 are made in 45 one piece of ticking with the corresponding sides of the two flaps or bolsters. When the bolsters are not raised my improved mattress has the appearance of any ordinary mat- tress and can be put to the same uses.

50 A frame, preferably made of wood, has two sections 6 and 7 which are hinged to each other by hinges 8. One of these sections is placed against the inner side of each flap 2 and is covered with ticking 9 on the 55 outer side so as to conceal the frame section

and upon the frame section the ordinary stuffing is placed and covered by the covering layers 3 and 4 and then tufted in the usual manner. Each flap is equal in thickness to one half of the thickness of the main body 1 and the frame sections can rest flat on each other with nothing between them but the two layers of ticking 9, which ticking is tacked to the frame sections. About 60 at the middle of one frame section 6 a metal rod 10 is mounted to turn axially and extends to the sides where it terminates in two handles 11, preferably made by bending the ends of the rod at right angles. The rod 10 is preferably located adjacent to the edge of a cross piece 12 of the frame 6. From said rod two struts 13 extend which can be engaged with the teeth of two racks 14 on the side pieces of the frame 7. By engaging the ends of the struts with the teeth of the 75 racks 14, the upper flap can be held at any desired inclination to the lower horizontal flap. A like adjustment of the upper flap can be obtained when the mattress is reversed.

The side members of the frame section 6 on which the rod is mounted are provided with grooves 15 into which the struts 13 can pass, so as to permit of folding one flap into close contact with the other, so that the mattress will be no thicker at the flaps or bolsters than at any other part of the body, when the flaps are folded down.

My mattress is very light and cheap and the person lying on the mattress never feels the wood as it is contained within the mat- tress and the flaps or bolsters are as soft as the body of the mattress.

Having described my invention what I claim as new and desire to secure by Letters Patent is:

The combination with a mattress body, split horizontally at one end, from side to side, to form two flaps or bolsters, of a frame composed of two rectangular sections 100 hinged to each other, at their inner ends, to move toward and from each other, at the ends opposite the hinges, which frame sections are both of the same width, so that the side pieces of the upper frame section when 105 lowered rest exactly on the side pieces of the lower frame section, a covering of bed ticking on the adjacent sides of the frames, stuffing on the outsides of the frame sections, a covering layer of ticking for the bolsters, 110

which is made in one piece with the covering of the corresponding face of the mattress, a rod mounted to turn axially on the upper frame section, struts projecting from said rod in line with the side pieces of the lower frame section, handles formed on the projecting ends of said rod, longitudinal grooves formed in the side pieces of the upper frame section, into which grooves the struts can be folded so as not to project beyond the inner surfaces of the frame sections, and racks set into the upper surfaces of the side pieces of

the lower frame section adapted to be engaged by the struts, substantially as set forth, whereby the mattress is reversible and either bolster may be elevated. 15

Signed at New York city, borough of Manhattan, in the county of New York and State of New York this 28th day of May, A. D. 1915.

ABRAHAM HARTMAN.
